UNITED STATES PATENT OFFICE.

THEODORE ABBOTT, OF PHILADELPHIA, PENNSYLVANIA, ASSIGNOR TO
JOHN C. GRAHAM, OF SAME PLACE.

DESIGN FOR FRINGE.

SPECIFICATION forming part of Design No. 13,889, dated May 8, 1883.

Application filed February 7, 1883. Term of patent 14 years.

To all whom it may concern:

Be it known that I, THEODORE ABBOTT, a citizen of the United States, residing in the city and county of Philadelphia, and State of Pennsylvania, have invented and produced a new and original Design for Fringe, of which the following is a specification, reference being had to the accompanying drawing, forming part thereof.

The drawing represents in front elevation a fringe which embodies my design, and in which A are pendants, each of which is of the form of what I term an "hour-glass spike," which spikes are spirally fluted as to their extremities and without flutes as to their central portions, ornamented with balls B, and attached to any suitable heading, C.

I claim—

1. A design for fringe, consisting of a heading, and of pendants of the form of hour-glass spikes, substantially as shown and described. 20
2. A design for fringe, consisting of a heading, and of pendants of the form of an hour-glass spike, ornamented with balls, as shown and described. 25

In testimony whereof I have hereunto signed my name this 29th day of January, A. D. 1883.

THEODORE ABBOTT.

In presence of—

J. BONSALL TAYLOR,
JOHN JOLLEY, Jr.
